PERFUMING DEVICE

Joseph Bonardi, New York, N. Y.

Application April 11, 1933, Serial No. 665,527

3 Claims. (Cl. 217—7)

This invention pertains generally to perfuming and pertains particularly to a device for perfuming wearing apparel by perfume vapors.

The use of complex compositions which by reason of their fragrance gratify the sense of smell dates back to the early ages. These complex compositions in concentrated form have been generally classified as oils of perfume. The perfumes of commerce are prepared from these oils by solution in alcohol or other suitable volatile solvent or solvents. In making perfume oils, flower oils are toned or blended with balsams, gums, oleoresins, etc., and small quantities of other substances such as extracts of animal origin are added, the purpose of which is to obtain the desired rate of evaporation, greater persistence and diffusiveness of odor, etc.

The quantity of perfume oil in solution in the perfumes of commerce is relatively small.

Practically all perfume oils, and in many cases their alcoholic solutions, have a tendency to stain delicate fabrics. Furthermore, alcoholic solutions of the better perfume oils must be used sparingly because of the persistence and strength of their odors. As a result when perfumes are used in liquid form, even though through the medium of an atomizer, it is practically impossible to diffuse the odor evenly to all parts of the clothing without exceeding good taste as to the strength of the odor.

This invention pertains to a device for the perfuming of clothing by means of perfume vapors, first, to avoid staining of the clothing by perfume liquids either in concentrated or diluted form, and second, to diffuse the odors evenly throughout the clothing, and to avoid spots of undesirably high or low odor concentration.

In one form of the invention a container for the clothing is provided and the perfume is contained in a pad of absorbent material which is arranged within the container in a manner so that only the vapors of the perfume may come into contact with the clothing. In another form of the invention the perfume impregnated absorbent material is confined within an inner perforated enclosure which is disposed within and in spaced relationship to an outer perforated enclosure. The outer enclosure prevents the clothing from coming into contact with the absorbent material held within the inner enclosure and thus prevents soiling of the clothing by liquid perfume.

Further features of the invention reside in the construction, arrangement, and combination of parts which, together with other features, will become more apparent to persons skilled in the art

as the specification proceeds and upon reference to the drawing in which:

Figure 1 is a perspective view of a container having the invention incorporated therein.

Figure 2 is a sectional plan view shown broken 5 of the container of Figure 1.

Figure 3 is a sectional end view shown broken of the container of Figure 1.

Figure 4 is a view similar to Figure 3 but illustrating a modification.

Figure 5 is a sectional elevation of another form of the invention.

Figure 6 is a sectional elevation illustrating a modified construction of the form of the invention illustrated in Figure 5.

Figure 7 is a sectional elevation of a further form of the invention.

Referring now more particularly to Figures 1, 2 and 3, at 10 is shown for the purpose of illustration a container 10 having a hinged cover 20 11 and a compartment 12.

Within the compartment 12 and spaced from the outer vertical circumferentially continuous wall 13 thereof is a circumferentially continuous vertical wall 15 which is secured to the bottom 16 25 of the compartment 12 as illustrated at 17 to form a liquid tight joint. Wall 15 is circumferentially perforated over substantially its entire area as illustrated at 18 except for a circumferential band portion 19 about its lower edge 30 which has no openings. A receptacle 20 for clothing is thus formed within the walls 15.

Strips of absorbent material 24 are shown disposed within the space 22 between walls 13 and 15, said absorbent material being held against the vertical wall 13. The strips of absorbent material 24 are shown held in place by vertical perforated holders 25 which in turn are spaced from the vertical walls 15. Any means may be provided to accomplish this spacing. As illustrated the ends of the holders 25 are secured at 26 to the vertical wall 13. Spacer members 27 attached to the vertical wall 15 assist in maintaining the holders 25 in spaced relationship with respect to wall 15 intermediate the ends of the 45 holders 25.

Closure members 30 shown hinged at 31 to the upper edge of the compartment 12 may be provided to close the space 22.

The operation of the form of the invention 50 shown in Figures 1, 2 and 3 is as follows. The strips of absorbent material 24 are impregnated preferably with oil of perfume and may in fact be saturated therewith. The clothing is placed within the receptacle 20 formed by the vertical 55

walls 15. The vapors from the perfume diffuse throughout the container 10, pass through the perforated wall 15 and come in contact with the clothing within the compartment 20. Since 5 clothing is generally arranged with horizontal folds, the vapors will readily find their way throughout all parts of the clothing and since the strips of absorbent material are preferably arranged vertically of the clothing and on all 10 four sides thereof, the concentration of vapors will be substantially uniform to substantially uniformly perfume the clothing.

Since the absorbent material 24 may be saturated with the oil of perfume (either in concentrated or diluted form), some of the liquid 15 may separate and collect at the bottom of the space 22. To avoid soiling the clothing the portion 19 of the vertical wall 15 is left unperforated and in view of the liquid tight joint at 17, such 20 perfume is prevented from finding its way into the compartment 20.

Renewals of oil of perfume may be made by changing the strips of absorbent material 24 or 25 by re-impregnating the same while in place, for instance by means of a dropper.

The clothing may be left in compartment 20 for 30 any desired period depending upon the degree of perfuming desired. For instance, clothing worn during the day may be placed in compartment 20 overnight and clothing worn at night may be placed in compartment 20 during the day.

To facilitate renewals, the absorbent material 24 may be made up into changeable cartridges 34. 35 Cartridges 34 may be held in place by any suitable means. As illustrated, fins 35 are attached to the vertical wall 13, fins 36 are attached to the outer surface of wall 15 and cartridges 34 are held therebetween. The cartridges 34 may be prepared and impregnated at the laboratory by the manufacturer and may be sold to the trade as such, in which case it is merely necessary for the user to replace any exhausted cartridge 34 by withdrawing it from the space 22 and inserting a fresh cartridge in its place.

45 The form of the invention shown in Figure 5, comprises a double walled enclosure 38, the inner wall 39 being substantially spaced from the outer wall 40. As illustrated the ball 38 is in two parts. The outer wall 40 is shown with overlapping portions at 41 for holding the two parts together and the two portions of the inner wall 39 are shown in contact at 42 to form a continuous enclosure for the absorbent material 43, although this is not essential and any means for 50 maintaining the absorbent material in spaced relationship to the outer wall 40 may be substituted.

55 The ball 38 is shown provided with rings 44 on opposite sides for holding the ball upright with either end up. Cups 45 are arranged so as to catch any liquid which might separate from the absorbent material 43.

The form shown in Figure 6 has a contour 60 similar to that of the ordinary cosmetic compact and comprises an outer perforated wall 48, an inner perforated wall 49 spaced from said outer wall 48 and an absorbent material 50 within the inner wall 49 for holding the oil of perfume. A hinge may be provided as shown at 51 65 and a clasp as shown at 52 if desired to provide for the renewals, or the parts may be spot welded or otherwise permanently secured together, in which case the device would be discarded after the liquid in the absorbent material 50 has 70 served its usefulness.

It will be noted that the outer walls 40 and 48 act as fenders to prevent clothing from coming into contact with the inner walls 39 and 49 respectively thus preventing any liquid from coming into contact with the clothing.

5 The cups 45 shown in Figure 5 are intended to be used when the absorbent material 43 is substantially saturated or oversaturated.

With the form shown in Figure 6 sufficient care 10 would be exercised in the impregnation so that the probability of separation of liquid from the absorbent material would be remote.

In the form shown in Figure 7 the double walled enclosure 54 comprising outer wall 55 and inner holder 56 for absorbent material 57 is combined with a lip stick or other similar cosmetic holder 58. The purpose is to automatically perfume the hands as a result of the use of the lip stick or other cosmetic. The device would ordinarily be carried in the user's hand bag or pocket 15 which it would also perfume or the device might be provided with shutters about the outer wall 55 which could be opened and closed when the device is in and out of use respectively. The cosmetic device 58 may be fixed or removable for 20 renewal purposes as desired.

Any of the forms illustrated can be made of 25 any suitable material such as base or precious metal or any of the plastics of which natural and synthetic resins and the cellulosic plastics are 30 representative.

The color or color combinations may obviously be varied without limit.

While certain of the walls are referred to as 35 being perforated it is to be understood that any equivalent means may be substituted such as any reticular material or mesh or other open structure capable of performing the same or analogous functions. The term perforated as used in the claims is intended to include such 40 equivalent structures.

Oils of perfume may be compounded so as to 45 have any desired consistency and rate of evaporation. The consistency may run from thin to thick or even to semi-solid or waxy forms, and the rate of evaporation may run from low to high boiling compositions. The material which has a high boiling point will of course have a much longer life.

The invention may be incorporated into any 50 device such as a double, triple or poly-compartment compact or may be attached to any object, and is capable of multitudinous forms and shapes.

It is of course understood that the higher the 55 degree of saturation, the longer will be the period between renewals or re-impregnation of the absorbent material and that substantial impregnation is preferred. In order to prevent any probability of soiling of the clothing by separating liquid, the special means illustrated in Figures 1, 2, 3, 4 and 5 for collecting any such liquid is provided.

Having described my invention, it is obvious 60 that many changes, omissions, additions, substitutions and modifications may be made therein within the scope of the claims without departing 65 from the spirit thereof.

I claim:

1. A device of the kind described comprising 70 a container having a compartment for storing clothing, a cover for said compartment, said compartment having an enclosing outer wall and a perforated inner wall spaced circumferentially from said outer wall and defining therebetween. 75

a continuous perfume distributing space completely surrounding the sides of said compartment, means to prevent flow of liquid along the bottom of said space into the bottom of said compartment, an absorbent material arranged in said perfume distributing space and adapted to contain a perfuming substance, and means for holding said absorbent material adjacent said outer wall and in spaced relation to said inner wall to prevent passage of liquid contained in said absorbent material through said perforated inner wall and to permit free circulation of perfume evolved from said absorbent material around and through the perforated side walls of said compartment.

2. A device of the kind described comprising a container having a compartment for storing clothing, a cover for said container and said compartment, said compartment having an imperforate outer wall and an inner wall spaced circumferentially from said outer wall and defining therebetween a perfume distributing space completely surrounding the sides of said compartment, said inner wall being secured to the bottom of said container to form a fluid tight joint and being fluid tight for a substantial distance above the bottom of said container to prevent passage of liquid along the bottom of said space into the bottom portion of said compartment, said inner wall further being perforated above said fluid tight portion and on the sides of said compartment, absorbent material arranged in said perfume distributing space and adapted to contain

a perfuming substance, a foraminous member secured to each of the outer side walls for holding said absorbent material in spaced relation to said inner wall, said perfume distributing space being otherwise unobstructed and permitting free circulation of perfume evolved from said absorbent material around and through the perforated side walls of said compartment, movable cover means fitting beneath the cover for said container and bridging the space between said outer and inner walls, and means carried by said cover means for co-operating with said inner wall to prevent lateral movement thereof.

3. A clothing perfuming device comprising a container having a compartment for storing clothing, a cover for said container, said container having an enclosing outer wall and a perforated inner wall spaced from said outer wall and defining therebetween a perfume distributing space along a plurality of sides of said compartment, means preventing the flow of liquid along the bottom of said space into the bottom of said compartment, an absorbent material arranged in said perfume distributing space and adapted to contain a perfuming substance, and means for holding said absorbent material adjacent said outer wall and in spaced relation to said inner wall to prevent passage of liquid contained in said absorbent material through said perforated inner wall and to permit free circulation of perfume evolved from said absorbent material through said perforated walls into said compartment.

JOSEPH BONARDI.
